UNITED STATES PATENT OFFICE.

RUBY G. EASTMAN, OF MARION, INDIANA, ASSIGNOR TO BENJAMIN F. BURK AND PHILIP MATTER, COPARTNERS AS FIRM OF NATIONAL SWEEPER COMPANY, OF MARION, INDIANA.

ROLLER-BEARING.

No. 848,642.

Specification of Letters Patent.

Patented April 2, 1907.

Application filed June 22, 1903. Serial No. 162,479.

To all whom it may concern:

Be it known that I, RUBY G. EASTMAN, a citizen of the United States, residing at Marion, in the county of Grant and State of Indiana, have invented a certain new and useful Improvement in Roller-Bearings, of which the following is a specification.

My invention relates to roller-bearings, particularly such as are adapted for use in connection with carpet-sweepers and carpet-sweepers equipped with such roller-bearings.

My invention is illustrated in one of its forms and some of its applications in the accompanying drawings, wherein—

15 Figure 1 is a plan view, with parts in section, of portions of the carpet-sweeper with my invention applied thereto. Fig. 2 is an enlarged cross-section of a carpet-sweeper wheel with my invention applied. Fig. 3 is a side elevation of same with the cap of the cup removed. Fig. 4 is a detail cross-section of the cup, taken near the retaining device. Fig. 5 is a cross-section through a roller and its retainer.

25 Like parts are indicated by the same letter in all figures.

A is a sweeper-brush; B, an axle; C, a spring-band which encircles the support. This band carries at the point D an inwardly-projecting short shaft, which is received into an aperture in the end of the brush, and on this the brush rotates. This band also bears against the hub of the sweeper-wheel E or against some projecting part associated with 35 the hub. It is preferably of spring material, so that the parts can be sprung into position. In both the wheel and sweeper-brush I insert my roller-bearing device, which is shown more in detail in Figs. 2, 3, and 4.

40 E is the wheel, having a central aperture into which fits the cup E', preferably of thin spun metal. In this cup lie the rollers, which are preferably arranged about a central retainer E², which has the central aperture E³ to receive the end of the shaft or axle and

45 has cut-away places or notches, as at E⁴, to receive the rollers E⁵. The retainer is of smaller diameter than the cup, and the notches E⁴ are of less depth than the diameter of the rollers, so that the rollers project in

both directions beyond the retainer. When the retainer and its associated rollers are inserted in the cup, they are thereby held together. The rollers are spaced and bear upon the inside of the cup and the outside of 55 the rollers, for the central aperture E³ is of such size that the axle bears upon the rollers. The rollers are provided each with a central annular groove into which the retainer fits.

F is a cap or lid, which fits closely onto the 60 cup and is perforated to admit the shaft B. This shaft B may be of such length as to bear against the bottom of the cup or pass through or be free from the bottom. When the device is applied, as indicated, in the carpet- 65 sweeper, it may be desirable to insert a fibrous washer J to keep the dust from entering the bearing through the aperture provided for the admission of the shaft.

What I have shown is simply for the purpose 70 of illustrating my invention and is of course not to be taken as the sole means by which it can be carried out. I do not wish to be limited to the particular form, arrangement, location, and size of these several parts 75 shown.

Use and operation of my invention are as follows: The hub of the wheel is either tooled out or it may be properly proportioned and finished in the casting. The cup, preferably of 80 spun material, is uncapped, and the rollers are placed loosely in position in the notches of the retainer. The group of rollers with their retainer are then put in position in the cup and the cap is forced down on the cup. Thus a 85 complete finished thin metal cup-bearing is provided with a shaft-aperture at one end. The cup is then forced into the aperture in the cup of the wheel, or if it is applied to the brush, then in the end of the brush. This 90 wheel or brush is now ready to be applied to the shaft or axle, as may be desired. The shaft may project through the other end of the cup, if necessary.

I claim—

95 A self-contained roller-bearing for carpet-sweepers and the like, comprising a cylindrical thin metal cup, a centrally-perforated cover therefor, a series of rollers therein each of approximately the same length as the cup 100

and adapted to bear against its ends when in position, and provided with an annular groove midway of its length, a retainer to keep the rollers distributed about the inner 5 surface of the cup, said retainer being in the form of a disk and with a central aperture and open notches on one of its edges, and

a flexibly-mounted shaft adapted to extend through the central perforation of the cover and in engagement with the rollers.

RUBY G. EASTMAN.
